UNITED STATES PATENT OFFICE.

ARTHUR A. KARCHER, OF CHICAGO, ILLINOIS, ASSIGNOR TO AMERICAN TOOL WORKS,
OF ST. JOSEPH, MICHIGAN, A CORPORATION OF MICHIGAN.

BREECH-LOADING AIR-GUN.

1,143,544.

Specification of Letters Patent. Patented June 15, 1915.

Application filed July 31, 1913. Serial No. 782,166.

To all whom it may concern:

Be it known that I, ARTHUR A. KARCHER, a citizen of the United States of America, and resident of Chicago, Cook county, Illinois, have invented a certain new and useful Improvement in Breech-Loading Air-Guns, of which the following is a specification.

My invention relates to air guns in general, but more particularly to those for use with projectiles of a certain character, such as darts or other devices of like nature, and especially guns of this kind which are provided with breech loading mechanism, it being understood that guns for use with projectiles of this kind cannot be loaded at the muzzle, and that it is necessary to insert the dart or other similar projectile at the rear end of the tube forming the barrel of the gun.

Generally stated, the object of my invention is to provide a novel and improved breech loading air gun of the foregoing general character.

25 A special object is to provide a novel and improved construction whereby an air gun having inner and outer barrels, the outer barrel being continuous and rigid from one end thereof to the other, can be operated as a breech loader, for the purpose of making the gun suitable for use with darts or other similar projectiles, which cannot be inserted at the muzzle of the gun, and whereby the said projectiles can be inserted in place at 35 the rear end of the inner barrel without the necessity of employing a break or joint in the length of the outer barrel.

Another object is to provide an improved construction and arrangement whereby an 40 air gun of this character is made operable as a breech loader by providing means for displacing the rear end of the inner barrel through the wall of the outer barrel, thus temporarily bringing the rear end of the 45 inner barrel into position affording access thereto for the purpose of inserting a dart or other projectile therein, the means for thus shifting the inner barrel from normal 50 position being exposed to the hand of the operator, and said means serving also as a closure for the opening in the outer barrel through which the inner barrel is brought 55 into position for loading.

It is also an object to provide certain 55 details and features of construction tending to

increase the general efficiency and serviceability of an air gun of this particular character.

To the foregoing and other useful ends my invention consists in matters hereinafter set forth and claimed.

In the accompanying drawings: Figure 1 is a side elevation of an air gun embodying the principles of my invention. Fig. 2 is an enlarged longitudinal section of the forward portion of the barrel of the gun shown in Fig. 1, the dotted lines indicating the positions of the barrel and the means for displacing the same through the slot in the under side of the outer barrel when it is desired to insert a dart or other projectile in the rear end of said barrel. Fig. 3 is a section on line 3—3 in Fig. 2. Fig. 4 is a section on line 4—4 in Fig. 2. Fig. 5 is a section on line 5—5 in Fig. 3. Fig. 6 is a section on line 6—6 in Fig. 3. Fig. 7 is a perspective of the pivoted lever to which the rear end of the inner barrel is connected, and which forms the closure for the slot in the under side of the barrel.

As thus illustrated, my invention comprises an outer barrel A of any suitable form or description, provided in the rear portion thereof with a compression chamber a having a plug a¹ firmly secured in the forward end thereof, which plug comprises a metal washer a², a leather washer a³ and an inner metal washer a⁴, the three washers being provided with a central aperture, and the aperture in the inner washer a⁴ being somewhat less in diameter than the two registering apertures in the other two washers. In this compression chamber a plunger B is provided, which plunger is operated by a spring b, the balance of the mechanism for compressing the air in this chamber, when the trigger C is pulled, being of any suitable, known or approved construction. The connections whereby the pivoted lever D is operative to retract the said plunger may also be of any suitable, known or approved construction.

The inner barrel E is inclosed in the outer end portion of the barrel A, the said outer barrel having its muzzle closed by a fixed washer a⁵ provided with a central opening a⁶ for the said inner barrel, said opening being surrounded on the inner surface of said washer by a collar a⁷, in the manner shown more clearly in Fig. 2. The said in-

2
 ner barrel E is provided with a shoulder e, and with a compression spring e¹, said spring being interposed between the sleeve a⁷ and the said shoulder, whereby outward movement of the inner barrel serves to compress the said spring. At its rear end the said inner barrel normally extends through the opening in the washers a² and a³ and engages the rim of the somewhat smaller opening in the washer a⁴, whereby the washer a⁴ serves as a stop or abutment against which the rear end of the inner barrel bears, and against which it is normally held by the tension of the said spring. The rear end of the said barrel is provided with a sheet metal member F which is bent around the barrel, the two end portions of the said member being left upstanding to provide a pair of vertically disposed and parallel flanges f, in the manner shown more clearly in Fig. 6. The lever G is formed from a piece of sheet metal, and is substantially trough shaped in form, its rear end being pivoted to the outer barrel at g, said outer barrel having its under side provided with a longitudinal slot a⁸ which permits the said lever to assume the position shown in Fig. 2. The upper and rear corners of the said lever are pivoted to the member F at g¹, the inner barrel being disposed within the trough or groove of the said lever and the latter having a forward metal or end portion g² that bears against the under side of the barrel when the inner barrel and lever are in normal position. It will be seen that the said inner barrel and operating lever thus provided are yieldingly held in normal position by the compression spring e¹, and that in such position the inner barrel is in condition to permit the discharge of the projectile therefrom. As the lever G is fully exposed to the hand of the operator, it follows that its forward handle portion g² can be easily grasped and pulled downward to bring the inner barrel into the position shown in dotted lines in Fig. 2. It will also be seen that this lever G has its lower side walls cut away at g³ to provide an opening through which the projectile can be inserted in the rear end of the inner barrel, when the parts are in the position shown in dotted lines in Fig. 2. When the inner barrel is thus displaced laterally through the side wall of the outer barrel, the said inner barrel moves forwardly or slides endwise in the washer a⁵, and the lever G, it will be seen, moves to a position which brings the pivotal point g¹ below the pivotal point g, whereby the tension of the spring e¹ serves to hold the inner barrel in loading position. Then, when the lever G is moved upward, the said spring returns the inner barrel and lever to normal position as soon as the pivotal point g¹ rises above the plane of the pivotal point g, the tension

of the spring thus serving to hold the inner barrel firmly in place, as well as to hold the handle portion g² of said lever firmly against the under side of the outer barrel.

The washer a⁴ serves to prevent the end-wise movable inner barrel E from moving backward, and the restricted opening in this washer serves also to prevent the dart or other projectile from being sucked backward and into the compression chamber 75 when the plunger G is drawn backward.

Thus, my invention contemplates a breech loading air gun having provisions for permitting the insertion of a dart or other projectile in the rear end of the inner barrel, 80 without the necessity of breaking or jointing the outer barrel, and without the necessity of removing the inner barrel. The inner barrel is simply displaced at its rear end in a lateral direction, to an extent sufficient to 85 bring it into position to permit the insertion of the projectile. Moreover, this is all accomplished in an air gun of the lever action type—that is to say, an air gun in which the lever is employed for drawing back the 90 plunger.

While I have shown and described a breech loading mechanism employing a pivoted lever for displacing the inner barrel through the side of the outer barrel, it is 95 obvious that various changes or modifications can be made, without departing from the spirit of my invention, as a substitute for the said lever, and for this reason I do not limit myself to the use of a lever for 100 operating the inner barrel, nor to the specific construction shown and described.

What I claim as my invention is:

1. An air gun comprising an outer barrel, an inner barrel, the outer barrel having an 105 opening, and means for displacing the inner barrel through said opening, to permit loading at the rear end of said inner barrel.

2. An air gun comprising an outer barrel, an inner barrel, the outer barrel having an 110 opening, and means for displacing the inner barrel through said opening, to permit loading at the rear end of said inner barrel, said means comprising a lever pivoted on the outer barrel and adapted to close said 115 opening when the inner barrel is in operative position.

3. An air gun comprising an outer barrel, an inner barrel, the outer barrel having an 120 opening, and means for displacing the inner barrel through said opening, to permit loading at the rear end of said inner barrel, said means comprising a movable element for closing said opening when the inner barrel is in operative position.

4. An air gun comprising an outer barrel, an inner barrel, the outer barrel having an 125 opening, and means for displacing the inner barrel through said opening, to permit loading at the rear end of said inner barrel,

1. A means comprising a movable element having an opening for permitting access to the rear end of said inner barrel.
2. An air gun comprising an outer barrel, an inner barrel, the outer barrel having an opening, and means for displacing the inner barrel through said opening, to permit loading at the rear end of said inner barrel, said outer barrel having a compression chamber from which the rear end of said inner barrel is disconnected by the operation of said means.
3. An air gun comprising an outer barrel, an inner barrel, the outer barrel having an opening, and means for displacing the inner barrel through said opening, to permit loading at the rear end of said inner barrel, and a support in which the forward portion of said inner barrel is movable endwise to permit said displacement of the rear end thereof.
4. An air gun comprising an outer barrel, an inner barrel, the outer barrel having an opening, means for displacing the inner barrel through said opening, to permit loading at the rear end of said inner barrel, and a compression spring for holding the inner barrel and said means in normal position.
5. An air gun comprising an outer barrel, an inner barrel, the outer barrel having an opening, means for displacing the inner barrel through said opening, to permit loading at the rear end of said inner barrel, a spring on said barrel, and an abutment against which said spring is compressed when the inner barrel is displaced through said opening.
6. An air gun comprising an outer barrel, an inner barrel, the outer barrel having an opening, and means for displacing the inner barrel through said opening, to permit loading at the rear end of said inner barrel, said means being operative to move the inner barrel forward.
7. An air gun comprising an outer barrel, an inner barrel, the outer barrel having an opening, and means for displacing the inner barrel through said opening, to permit loading at the rear end of said inner barrel, said means being attached to the outer barrel and exposed to the hand of the operator.
8. An air gun comprising an outer barrel, an inner barrel, the outer barrel having an opening, and means for displacing the inner barrel through said opening, to permit loading at the rear end of said inner barrel, said means being movable within the outer barrel, and a spring for holding the inner barrel in place, said outer barrel having an opening through which the lower end of said inner barrel is displaced when moved forward.
9. An air gun comprising an outer barrel, an inner barrel, the outer barrel having an opening, and means for displacing the inner barrel through said opening, to permit loading at the rear end of said inner barrel, the rear end portion of the inner barrel being displaceable through said opening.
10. An air gun comprising an outer barrel, an inner barrel, the outer barrel having an opening, and means for displacing the inner barrel through said opening, to permit loading at the rear end of said inner barrel, the rear end portion of the inner barrel being displaceable through said opening.
11. An air gun comprising an outer barrel, an inner barrel, the outer barrel having an opening, and means for displacing the inner barrel through said opening, to permit loading at the rear end of said inner barrel, and means on the inner barrel for engaging the outer barrel to limit the said displacement.
12. An air gun comprising an outer barrel, and an outer barrel having an opening therein, permitting loading at the rear of said inner barrel, the rear end portion of the inner barrel being displaceable through said opening.
13. An air gun comprising an inner barrel, an outer barrel which is rigid throughout the length thereof, provided with a compression chamber and mechanism therein, and having an opening for loading at a point immediately in front of said chamber, the rear end portion of the inner barrel being displaceable through said opening.
14. An air gun comprising an inner barrel, an outer barrel which is rigid throughout the length thereof, provided with a compression chamber and mechanism therein, and having an opening for loading at a point immediately in front of said chamber, said opening permitting the placing of a dart in position for discharge from the gun, the rear end portion of the inner barrel being displaceable through said opening.
15. An air gun comprising a barrel which is rigid throughout the length thereof, provided with a compression chamber and mechanism therein, and having an opening for loading at a point immediately in front of said chamber, an inner barrel, and means cooperating with said opening to permit insertion of the projectile at the extreme rear end of said inner barrel, the rear end portion of the inner barrel being displaceable through said opening.
16. An air gun comprising a barrel which is rigid throughout the length thereof, provided with a compression chamber and mechanism therein, and having an opening for loading at a point immediately in front of said chamber, an inner barrel, and means for shifting the inner barrel relative to said opening, to permit insertion of the projectile at the rear end of said inner barrel, the rear end portion of the inner barrel being displaceable through said opening.
17. An air gun comprising an outer barrel with a fixed closure at the outer end thereof, an inner barrel slidably endwise in said closure, and means for raising and lowering the rear end of said inner barrel.
18. An air gun comprising an outer barrel with a fixed closure at the outer end thereof, an inner barrel slidably endwise in said closure, a spring subject to tension by the endwise motion of said inner barrel, and means for raising and lowering the rear end of said inner barrel.
19. An air gun comprising an outer barrel, an inner barrel movable within the outer barrel, and a spring for holding the inner barrel in place, said outer barrel having an opening through which the lower end of said inner barrel is displaced when moved forward.
20. An air gun comprising an outer barrel, an inner barrel movable within the outer barrel, a spring for holding the inner barrel in place, and a lever at the lower side of said outer barrel for displacing the said inner barrel from normal position, said outer barrel

- rel having an opening through which the lower end of said inner barrel is displaced when moved forward.
21. An air gun comprising an outer barrel with a fixed closure at the outer end thereof, an inner barrel slidable endwise in said closure, a compression chamber normally connected with the rear end of said inner barrel, but disconnected therefrom by the movement of said inner barrel, and means for turning the inner barrel at an angle to the outer barrel for loading purposes.
22. An air gun comprising an outer barrel with a fixed closure at the outer end thereof, an inner barrel slidable endwise in said closure, a spring subject to tension by the endwise motion of said inner barrel, a compression chamber normally connected with the rear end of said inner barrel, but disconnected therefrom by the movement of said inner barrel, and means for turning the inner barrel at an angle to the outer barrel for loading purposes.
23. An air gun comprising an outer bar-
- rel, an inner barrel movable within the outer barrel, a spring for holding the inner barrel in place, and a compression chamber normally connected with the rear end of said inner barrel, but disconnected therefrom by the movement of said inner barrel to a position at an angle to said outer barrel.
24. An air gun comprising an outer barrel, an inner barrel movable within the outer barrel, a spring for holding the inner barrel in place, a lever at the lower side of said outer barrel for displacing the said inner barrel from normal position, and a compression chamber normally connected with the rear end of said inner barrel, but disconnected therefrom by the movement of said inner barrel to a position at an angle to said outer barrel.

Signed by me at Chicago, Illinois, this 23d day of July 1913.

ARTHUR A. KARCHER.
